UNITED STATES PATENT OFFICE.

EARL H. ISRAEL, OF ST. LOUIS, MISSOURI, ASSIGNOR TO THE L. M. RUMSEY
MANUFACTURING COMPANY, OF SAME PLACE.

DESIGN FOR A WATER-CLOSET COVER.

SPECIFICATION forming part of Design No. 24,642, dated August 27, 1895.

Application filed July 2, 1895. Serial No. 554,769. Term of patent 7 years.

To all whom it may concern:

Be it known that I, EARL H. ISRAEL, of the city of St. Louis, in the State of Missouri, have invented and produced a new and original Design for Water-Closet Covers, of which the following is a specification, reference being had to the accompanying drawings, forming part hereof.

The leading feature of my design consists
o in the oval seat having ornamental rear-
wardly-projecting wings at its back.

In the drawings, Figure I is a top or plan view of my design, and Fig. II is an edge view.

The front and sides A B of the lid and seat are oval, and the back C and D of the lid and seat are flat. Projecting rearwardly from the back of the seat are ornamental wings E, having hinge-like unions F with the lid and seat. At the back of the lid is a bar G.

I claim as my invention—
The design of a water-closet cover, substantially as herein shown and described.

EARL H. ISRAEL.
